UNITED STATES PATENT OFFICE.

EDWARD WILLIAM CARROLL, OF WESTON, WEST VIRGINIA.

POST CONSTRUCTION.

Application filed May 26, 1923. Serial No. 641,732.

To all whom it may concern:

Be it known that I, EDWARD W. CARROLL, a citizen of the United States, residing at Weston, in the county of Lewis and State 5 of West Virginia, have invented a new and useful Post Construction, of which the following is a specification.

This invention relates to post construction, and aims to provide novel means for 10 supporting a post to insure against deterioration of the post at its base.

Another object of the invention is to provide a separable post, novel means being provided for locking the post to its base.

15 A further object of the invention is the provision of novel means for securing the fence structure to the post, eliminating the use of nails, bolts or similar securing means.

With the foregoing and other objects in 20 view which will appear as the description proceeds, the invention resides in the combination and arrangement of parts and in the details of construction hereinafter described and claimed, it being understood 25 that changes in the precise embodiment of the invention herein disclosed, may be made within the scope of what is claimed, without departing from the spirit of the invention.

30 Referring to the drawing:

Figure 1 is an elevational view disclosing a post constructed in accordance with the invention.

Figure 2 is a fragmental elevational view 35 of the post, a portion of the base being in section.

Figure 3 is a sectional view on line 3—3 of Figure 2.

Figure 4 is a sectional view through the 40 upper portion of a post base and disclosing a modified form of the invention.

Figure 5 is a sectional view on line 5—5 of Figure 4.

45 Referring to the drawing in detail, the reference character 5 designates a post base which is formed of concrete or similar plastic material and provided with a head 6 at its upper end, which head is formed with an opening to accommodate the post 7 associated therewith.

50 The bottom wall of the opening of the head 6 is inclined as at 8, so that any moisture entering between the post and its base, may drain therefrom, openings 9 communicating with the opening in the head to allow the fluid to pass therefrom. Formed

integral with the wall of the opening in the head 6 is an inwardly extended lug 10 adapted to enter the groove 11 when the post section 7 is positioned in the head, the 60 groove 11 being in communication with the groove 12 formed at right angles with the groove 11 so that when the post is positioned in the head and slightly rotated, the lug will lock the post to its base in a 65 manner as clearly shown by Figure 2 of the drawing.

The post 7 carries suitable fence securing irons 14 whereby the wires of the fence may be hooked thereover, the bottom wire 70 of the fence structure which is indicated at 15 being positioned in the groove 16 formed in the outer surface of the head 6. This groove 16 is curved upwardly, at its ends so that when the bottom wire 15 is positioned, it is necessary to stretch the wire 75 15 into position.

In order that the post will be held firm it is contemplated to position sand or gravel, which is indicated by the reference character 80 17 and shown by Figure 2 of the drawing, the sand or gravel permitting the moisture to pass downwardly therethrough.

As shown by Figure 4 of the drawing, the post which is indicated by the reference character 18 is formed with a groove 19 communicating with the groove 20 that is formed in the outer surface of the post at a point adjacent to the lower end thereof, the groove 19 communicating with a groove 90 21 formed in the post 18, the groove 21 also communicating with a groove 22 also formed in the head of the base.

When it is desired to connect the post 18 with its base, roller 23 is dropped into the 95 registering grooves, which roller gravitates to a position as shown by Figure 4 locking the post against movement within its base. From the foregoing it will be seen that if a fence post becomes broken or otherwise rendered incapable of supporting a fence, the fence post may be readily and easily replaced.

100 What is claimed as new is:

1. In a fence post construction, a base section having a post opening and having a groove formed therein, said groove being formed with a right angled end portion, a post section having a groove adapted to register with the first mentioned groove when the post is fitted in the base section, and a roller of a width to extend into both 105 110 115

grooves when the roller is dropped into the base section.

2. In a fence post construction, a base having an opening and having a downwardly extended groove formed with a right angled end portion, a post section adapted to be fitted in the opening of the base, said post section having a groove corresponding to the first mentioned groove, and a roller adapted to be fitted in the

grooves to lock the post section to the base section.

In testimony that I claim the foregoing as my own, I have hereto affixed my signature in the presence of two witnesses.

EDWARD WILLIAM CARROLL.
